UNITED STATES PATENT OFFICE.

TIMOTHY E. WHALEN, OF ROCHESTER, NEW YORK.

DESIGN FOR A CALENDAR.

SPECIFICATION forming part of Design No. 13,168, dated August 8, 1882.

Application filed May 12, 1882. Term of patent 3½ years.

To all whom it may concern:

Be it known that I, TIMOTHY E. WHALEN, of Rochester, in the county of Monroe and State of New York, have invented a new and Improved Design for a Calendar, of which the following is a full, clear, and exact description.

The invention consists of a new and original design for a calendar composed of a horseshoe-border and a trefoil arrangement within the border, as hereinafter more fully set forth.

Reference is to be had to the accompanying drawing, forming part of this specification, which is a front elevation of a calendar-face constructed according to my design.

15 A represents the border or margin of the

calendar-face figured in the form of the bottom of a horseshoe, and B represents the facets of the trefoil arrangement of the different parts of the calendar.

Having thus fully described my invention, I claim as new and desire to secure by Letters Patent—

The design for a calendar, consisting of the horseshoe-border and trefoil arrangement of the part within the border.

TIMOTHY E. WHALEN.
